(57) **CLAIM**

The ornamental design for an elongated flooring member, formed as an inverted channel, attached to a wooden plank, having a non-slip tread, as shown and described.

DESCRIPTION

FIG. 1 is a left end elevation of the elongated flooring member, formed as an inverted channel attached to a wooden plank, having a non-slip tread, showing my new design, the right end elevation being identical;

FIG. 2 is a top plan view thereof;

FIG. 3 is a front elevation thereof, the rear elevation being identical;

FIG. 4 is a bottom plan view thereof;

FIG. 5 is a fragmentary plan view of a tread pattern on an upper surface thereof;

FIG. 6 is a fragmentary transverse cross-sectional view of the tread pattern taken along line 6—6 of FIG. 5;

FIG. 7 is a fragmentary longitudinal cross-sectional view of the tread pattern taken along line 7—7 of FIG. 5; and,

FIG. 8 is a perspective view of the elongated flooring member, formed as an inverted channel attached to a wooden plank, having a non-slip tread, of FIG. 1.

FIGS. 2—4 and 8 are shown broken away to indicate indeterminate length.
